DESIGN FOR A FLOOR COVERING OR THE LIKE

Charles D. Lehner, Long Island City, N. Y., assignor to Bigelow-Sanford Carpet Co., Inc., Thompsonville, Conn., a corporation of Massachusetts

Application May 5, 1939, Serial No. 84,822

Term of patent 7 years

To all whom it may concern:

Be it known that I, Charles D. Lehner, a citizen of the United States, residing at Long Island city, in the county of Queens and State of New York, have invented a new, original, and ornamental Design for a Floor Covering or the like, of which the following is a specification, reference being had to the accompanying drawing, forming a part thereof.

The drawing is a plan view of a floor covering or the like showing my design, a complete unit of which is delineated by dot dash lines.

I claim:

The ornamental design for a floor covering or the like, substantially as shown and described.

CHARLES D. LEHNER.
